UNITED STATES PATENT OFFICE

RAYMOND N. EHRHART, OF PITTSBURGH, PENNSYLVANIA, ASSIGNOR TO ELLIOTT COMPANY, OF PITTSBURGH, PENNSYLVANIA, A CORPORATION OF PENNSYLVANIA

APPARATUS FOR EVAPORATING LIQUID

Application filed June 3, 1926. Serial No. 113,427.

The present invention relates broadly to the art of heat exchanging and liquid treatment, and more particularly to an improved apparatus for the evaporation of liquids.

5 In the art to which the present invention relates, it is a customary practice to utilize high pressure steam for the development of energy in mechanical or other forms, the steam in passing through the particular apparatus used giving up a certain portion of its thermal energy. This portion of thermal energy so given up is in turn transformed by the apparatus into another form of energy such as mechanical energy. The greater portion 10 of the thermal energy of the steam, however, is not utilized by the apparatus, so that the steam rejected thereby carries away with it by far the greater portion of its original thermal energy. In other words, the thermal 15 energy in the exhaust of standard apparatus, such for example, as a steam engine, is many times that which has been utilized by the engine. The thermal energy content of exhaust steam under such conditions is usually 20 referred to as degraded or lower level heat.

In the operation of apparatus utilizing steam, it is necessary in order to obtain the maximum range for the utilization of heat to have the apparatus exhaust into a region 25 having the lowest possible, or at least the lowest practical pressure, which in connection with steam means the lowest temperature. For practical purposes such a condition of low pressure is conveniently produced by 30 means of a condenser, the temperatures maintained by a condenser usually being so low that there is no way of utilizing all of the low level heat in the range as maintained by the condenser. It is, however, possible to reclaim 35 small portions of the low level heat that would ordinarily be rejected to the condenser, and it is with this phase of the operation that the present invention deals. One object of the 40 present invention, therefore, is to effect a saving and practical utilization of a portion of the degraded heat which is ordinarily thrown away.

In the accompanying figure of the drawing, which figure is largely diagrammatic and representative of one embodiment of the in-

vention, I have shown for purposes of illustration only one system by means of which the invention may be carried out and a portion of the low level heat effectively utilized.

In carrying out the present invention there 55 may be provided a condenser 2 of the two-surface type and of any desired construction and hereinafter referred to as the main condenser. Water may be circulated through the tubes of the condenser by a suitable pump 60 3 and discharged therefrom through an outlet 4, while steam may be delivered to the space around the tubes through the inlet 5, such steam obviously being led from the engine or other apparatus which the condenser 65 serves. Usually, all of the heat in the exhaust steam delivered through the inlet 5 is communicated to the cooling water supplied to the condenser which cooling water in turn, goes to waste. In accordance with the present invention, a portion of the heat which is thus normally wasted is diverted and utilized 70 in a process of liquid evaporation effective for evaporating a sufficient quantity of raw water for example, to make up the losses in distilled 75 water incident to normal power plant operation.

In accordance with this feature of the invention I may provide the main condenser with an offtake conduit 6 through which a 80 portion of the exhaust steam led to the main condenser may be conducted to a second condenser 7, this condenser being hereinafter referred to as a heater condenser. The heater condenser is materially smaller in size than the main condenser but may otherwise be of a construction generally similar thereto. Cooling water for the heater condenser may be delivered through a conduit 8 and discharged through a connection 9 hereinafter 85 more fully referred to. Cooperating with the heater condenser is an air exhausting means 10 herein illustrated as discharging through the conduit 11 directly into the main condenser. As the pressure in the main condenser is not materially different from that in the heater condenser, it will be apparent 90 that for but a small expenditure of steam in an exhausting means, for example of the ejector type, a relatively large exhausting 95 100

capacity may be realized. By the use of a relatively large exhausting means the efficiency of the heater condenser may be made comparatively much greater than is possible for practical operating reasons with the main condenser. For purposes of illustration only, and not for limiting the present invention, it may be pointed out that a main condenser requires such differences in heat head between the water and steam spaces that the discharge water is usually at least 10° and generally 15° lower in temperature than the temperature of the steam being condensed. Also, condensers with ejecting or exhausting means of the general character illustrated by the exhausting means 10 for the heater condenser require a much less heat head. For example, a 2,000 square foot condenser receiving steam from the inlet of the main condenser will extract 18,000 pounds of steam per hour, and the circulating water leaving such condenser will be heated to within a fraction of a degree of the temperature of the heating steam. I also find that such results are accomplished with a steam ejector having a steam consumption of but 50 pounds an hour, such an operation being obtainable with an exhausting

greater in all cases than the vacuum maintained in the main condenser. I have found that it is possible to so proportion the high vacuum condenser with respect to surface area, amount of circulating area, and the like, that it is practically possible to continuously maintain a vacuum therein, the incident steam temperature of which is from 10 to 15° lower than that in the main condenser. 70

The high vacuum condenser 14 has its vapor space operatively connected through a suitable conduit 15 with the vapor offtake 16 from a flash chamber 17. By reason of this relationship, there is maintained in the vapor space of the flash chamber the same high vacuum which exists in the vapor space of the high vacuum condenser. The circulating water from the heater condenser passes through the outlet 9 directly to the flash chamber. In view of the fact that the heater condenser maintains a high temperature in the circulating water discharged thereby, while the condenser 14 maintains a high vacuum, the water passing through the connection 9 to the flash chamber will be at a temperature higher than the temperature of the flash chamber, whereby a certain portion 85

thereof will flash into steam, this flashing or

flow being operatively with the exhausting 90
from the pump 20. Some of the pump, such as the outlet 9, will be connected with the heater condenser 14, and the steam will be exhausted from the outlet 9 to the flash chamber 17.

95

passing by means of suitable connections 24 through the inter and after condensers. From the foregoing description it will be apparent that I am enabled by means of low level temperature steam to heat water to be evaporated to substantially the maximum temperature possible, and thereafter flash a part of this water in a chamber having a vacuum maintained therein of such a degree that the heated water will flash. Thereafter, the flashed water is condensed, recovered, and delivered to the desired point as distilled water.

I am aware that it has heretofore been proposed, as illustrated for example in the patent to Forbes, No. 1,232,269 of July 3, 1917, to take water from the discharge of a main surface condenser and flash it to obtain distilled water. Installations of this character, however, have not been feasible or practical from a commercial standpoint for the reason that with such condensers there is very little rise in the temperature of the circulating water, and therefore, no opportunity for obtaining a sufficient heat head to insure satisfactory operation. Furthermore, any falling off in the efficiency of the condenser will result in even poorer operation. In all cases of such nature it is proposed to flash the water in a flash chamber, the vacuum of which corresponds to the vacuum of the main condenser from which the water is extracted. In accordance with the present invention I not only overcome difficulties of the nature referred to, but provide means for increasing in a very effective manner the heat in a certain quantity of water and then flashing this water in a flash chamber having a vacuum maintained therein which is higher than the vacuum maintained in the main condenser. As a part of my installation I have also disclosed exhausting means for the high vacuum condenser capable of giving very efficient performance. It is so proportioned as to have the ability to withdraw gases and vapors from the high vacuum condenser with a vacuum existing therein of greater magnitude than is ordinarily encountered in condenser installations. As an example of this condition, it will be found that main condensers with water temperatures incident to the winter season will maintain vacua the temperatures of which are 70° or even lower. In such cases, if I wish to obtain flash gradients of 15°, there must be provided an ejector capable of handling fluid from the high vacuum condenser, the pressure of which fluid in inches of mercury is less than .4 of an inch absolute. While the invention is disclosed herein as embodying a main condenser of the surface type, the utility of the invention is not limited with respect thereto as the present invention will operate effectively with a main condenser of the jet type. I further realize that while the present embodiment of the invention illustrates utilizing

ing heating steam from the main condenser for the heater condenser, low level steam for this purpose may be taken from other sources as for example from the low pressure stages of a steam turbine or from the intermediate receiver of a steam engine of the reciprocating type. The present drawing is illustrative only of a preferred embodiment of the invention for the purpose of setting forth the principles of operation thereof and does not define the limits of my invention as changes in the construction and operation may be made without departing either from the spirit of the invention or the scope of my broader claims.

Also, while I have herein referred to a flash temperature gradient of 10 or 15°, and while, for practical purposes it is desirable to have a flash temperature gradient as high as possible, I find that a 5° gradient will give fairly satisfactory operation. It is desirable, however, under the majority of conditions to maintain a temperature gradient for flashing purposes in excess of 5°.

Certain advantages of the present invention arise from the provision of an apparatus by means of which it is possible to reclaim small portions of the low level heat that are ordinarily rejected to the main condenser.

Other advantages of the present invention arise from the provision of an apparatus operating to recover the thermal energy of degraded or low level heat and utilizing such energy for the production of distilled water.

Still further advantages of the present invention arise from the method of treating liquids in such manner that the thermal energy of degraded or low level heat may be effectively utilized for producing temperatures sufficiently high that evaporation of certain quantities of liquid may be obtained and the energy of such steam thereby recovered.

I claim:

1. In a heat exchange apparatus, a main condenser, a heater condenser, means for supplying low level vapor to said condensers, a gas offtake from the heater condenser to the main condenser, means for maintaining a lower pressure in the heater condenser than in the main condensers, a flash chamber receiving water from said heater condenser, and means maintaining a lower pressure in said flash chamber than the pressure in said main condenser.

2. In a heat exchange apparatus, a main condenser, a heater condenser, means for supplying low level vapor to said condensers, a gas offtake from the heater condenser to the main condenser, means for maintaining a lower pressure in the heater condenser than in the main condensers, a flash chamber receiving water from said heater condenser, and means maintaining a lower pressure in

said flash chamber than the pressure in the vapor inlet of said main condenser; said last mentioned means comprising a high vacuum condenser.

5 3. In a heat exchange apparatus, a main condenser, a heater condenser, means for supplying low level vapor to said condensers, a gas offtake from the heater condenser to the main condenser, said offtake including exhausting means, a flash chamber receiving water from said heater condenser, and means maintaining a lower pressure in said flash chamber than the pressure in vapor inlet of said main condenser.

10 4. In a heat exchange apparatus, a main condenser, a heater condenser, means for supplying low level vapor to said condensers, a gas offtake from the heater condenser to the main condenser, said offtake including exhausting means; a flash chamber receiving water from said heater condenser, and means maintaining a lower pressure in said flash chamber than the pressure in vapor inlet of said main condenser, said last mentioned 20 means comprising a high vacuum condenser.

25 5. In a heat exchange apparatus, a main condenser, a heater condenser, air exhausting means for the heater condenser delivering to the main condenser, a flash chamber, means for delivering water from the heater condenser to the flash chamber, and means for obtaining in said flash chamber a flash 30 temperature gradient at least equal to 5° F.

35 6. In a heat exchange apparatus, a main condenser, a heater condenser, air exhausting means for the heater condenser delivering to the main condenser, a flash chamber, means for delivering water from the heater condenser to the flash chamber, and means for 40 obtaining in said flash chamber a flash temperature gradient at least equal to 5° F., said means comprising a high vacuum condenser.

45 7. In a heat exchange apparatus, a main condenser, a heater condenser, air exhausting means for the heater condenser delivering to the main condenser, a flash chamber, means for delivering water from the heater condenser to the flash chamber, and means for obtaining in said flash chamber a flash 50 temperature gradient at least equal to 5° F., said means comprising a high vacuum condenser in combination with a multi-stage air ejecting means.

55 8. In a heat exchange apparatus, a main condenser and a heater condenser, means for supplying both steam and water to said condensers in parallel, and means for maintaining a lower pressure in the heater condenser than in the main condenser.

60 9. In a heat exchange apparatus, a main condenser and a heater condenser, means for supplying both steam and water to said condensers in parallel, and means for maintaining a lower pressure in the heater con-

65 denser than in the main condenser, said means discharging into the main condenser.

70 10. In a heat exchange apparatus, a main condenser and a heater condenser, means for supplying both steam and water to said condensers in parallel, means for maintaining a lower pressure in the heater condenser than in the main condenser, a flash chamber, and means for conducting heated water from the heater condenser to the flash chamber.

75 In testimony whereof I have hereunto set my hand.

RAYMOND N. EHRHART.
